Attorney.

UNITED STATES PATENT OFFICE

IRWIN GUTMAN, OF PITTSBURGH, PENNSYLVANIA

SEPTIC TANK

Application filed March 7, 1930. Serial No. 433,922.

My invention relates to septic tanks and more particularly to the cover and baffle portions thereof, although it is capable of use in connection with various other structures, 5 such as grease traps, etc.

One object of my invention is to provide a sanitary tank cover of such form that it may be mounted on standard tile sections which form the tank body proper, and which serves 10 as a support for baffles that may be of standard half-round tile or channel pipe sections.

Another object of my invention is to provide an attachment of light weight that may be shipped great distances at low cost, without danger of damage, and which may be 15 readily assembled with tank bodies at the place of installation, by unskilled workmen.

Still another object of my invention is to provide a structure wherein it is not necessary to form baffles integrally with any part 20 of the septic tank structure, thus reducing cost of manufacture and losses through damage in handling.

Still another object of my invention is to 25 simplify and improve septic tank structures generally.

One form which my invention may take is shown in the accompanying drawings, wherein in Figure 1 is a plan view of a tank structure; 30 Fig. 2 is a perspective view, in section, of a portion of the tank cover; Fig. 3 is a vertical sectional view of the structure of Fig. 1; Fig. 4 is a view taken on the line IV-IV of Fig. 1, Fig. 5 shows a modification of the structure of Fig. 3, and Fig. 6 shows still another 35 modification thereof.

The tank body is shown as including an upper tile section or crock 5 of ordinary form and provided with an inlet opening 6 and an 40 outlet opening 7, through which sewage or other liquid may be admitted and discharged, through conduits or sewer or drain tile (not shown) in the usual manner.

The tiles 5 and 8 which constitute the body 45 portion of the tank may be of ordinary form as well-known in the art. It has been customary to form baffles integrally with these tile sections, at the factory, and then ship the tile sections, sometimes through long distances, to the place of installation. The cost of such

specially-formed tiles is expensive, the freight is considerable, and a considerable loss results through breakage in handling. With burned-in baffles, septic tank freight rate applies, while pipe with holes is shipped 55 at a lower rate, as sewer pipe.

In order to avoid the necessity of forming baffles on these tile sections, I provide a cover 9 that may be stamped from sheet metal or formed otherwise. These covers may be 60 made at a central point and shipped to the customers, who usually find sewer tile readily available at points near home. The metal cover is provided with a down-turned flange 10 that will hold it centralized on the tile 5 and prevent access of surface water to the tank. A pair of arcuate slots are formed by 65 stamping down portions 11. The slots are of such size that they will receive standard half-round tile or channel pipe sections 12, which 70 serve as baffles opposite the openings 6 and 7. The tongues 11 are provided with extensions or lugs 13 which serve to hold the baffle members 12 against displacement relative to the 75 openings 6 and 7, the bellied ends of the members 12 preventing them from falling into the tank.

In Fig. 5, I show a modified arrangement for holding the baffle members securely 80 against displacement, wherein a holding member or rod 14, which may be made from spring metal, is provided with down-turned ends 15 that are sprung into position over the bellied ends of the baffles.

In Fig. 6, the baffles are secured against displacement by means of holding members 17 85 which are secured to the cover in any suitable manner. The members 17 may be formed from suitable spring metal so that when the baffles are positioned on the cover, the members 17 may be sprung over the ends thereof, thereby detachably supporting the baffles.

Not only is a structure made according to 90 my invention much cheaper than various previous structures and more convenient of installation, but in case of clogging, the tiles may be readily lifted from the tank, the walls of the arcuate slots serving to scrape them 95 clear of adhering solids. The arcuate slots are so positioned that the vertical edges of the 100

baffle members will abut against the wall of the crock 5, as shown more clearly in Fig. 4, while at the same time, the belled end of the crock 5 provides a passage for the circulation of gases in the upper part of the tank.

5 Furthermore, since the baffles extend downwardly through the cover plate and into the tank, incoming sewage or liquid is prevented from disturbing the bacteria mat. In a usual 10 type of baffle, the inlet opening is only slightly below the upper edge of the baffle over which the sewage may splash when entering the tank and disturb the mat.

I claim as my invention:—

15 1. A cover for septic tanks and the like having a slot therein for permitting insertion of a baffle member, and means depending from said cover for supporting the baffle member against displacement in a direction transversely of said member.

20 2. A cover for septic tanks and the like consisting of a sheet metal member having an arcuate slot formed therein for the reception of a baffle member, and having a down-turned flange for holding the baffle member vertically-aligned in a tank body.

25 3. The combination with a septic tank body having inlet and outlet passages, of a cover therefor having openings, baffle members extending through said openings at points adjacent to said passageways, and means for supporting the baffle members against displacement relative to said passages.

30 4. The combination with a septic tank body having a passageway through one wall thereof, of a cover therefor having an opening therein, a baffle member extending through said opening at a point adjacent to said passage, and means for supporting said baffle member against displacement relative to said passage.

35 5. A septic tank structure comprising a body and cover therefor provided with a slot, a baffle member of half-round belled end tile 40 section extending through said slot, with its enlarged end resting on the top of the cover, and means within said body member for preventing displacement of the tile section in a lateral direction.

45 50 In testimony whereof I, the said IRWIN GUTMAN have hereunto set my hand.

IRWIN GUTMAN.
